to Ford Motor Company, Dearborn, Mich., a corporation of Delaware

Filed Jan. 31, 1962, Ser. No. 68,586

Term of patent 7 years

(Cl. D14—18)

FIG. 1 is a perspective view of an automobile grille, showing my new design. It being understood that the fragmentarily shown grille pattern is continuous as shown in FIG. 2;

FIG. 2 is a front elevational view of the automobile grille;

FIG. 3 is a top plan view;

FIG. 4 is an enlarged side elevational view; and

FIG. 5 is an enlarged sectional view taken substantially through line 5-5 of FIG. 2.

I claim:

The ornamental design for an automobile grille, substantially as shown and described.
